(57) **CLAIM**

The ornamental design for a braided stent, as shown and described.

DESCRIPTION

FIG. 1 is a perspective view of a braided stent showing my new design;

FIG. 2 is a front elevational view with the rear view being a mirror image thereof;

FIG. 3 is a top view with the bottom view being a mirror image thereof; and,

FIG. 4 is a right side elevational view with the left side being a mirror image thereof.

The brackets shown in the figure drawings indicate indeterminate length.
